FLOAT

Reginald M. Banks and Dorothy A. Banks,
Woodmere, N. Y.Continuation of application Serial No. 220,456,
July 21, 1938. This application March 13, 1939,
Serial No. 261,624

15 Claims.

(Cl. 9—11)

Our invention relates to a float adapted particularly, although not necessarily, for recreational purposes.

The invention, in an important aspect, relates to a float formed from one or more buoying means disposed within a suitable supporting casing.

The invention, in another important aspect, relates to the provision of buoying means and an associative casing of such character that the parts may readily be assembled or disassembled by a simple operation.

According to the preferred form of our invention the casing comprises a plurality of substantially circular or disc-like compartments each adapted to house an inflated annular tube and arranged in series abutting along a common sector line of sufficient length to give substantially longitudinal rigidity to the float when the tubes are inflated, the adjacent compartments being separated by a partition along said sector line and preferably stout enough to prevent the inflated tube in either compartment from substantially bulging the partition across the normal sector line if the tubes in the compartments should be unevenly inflated. The casing is preferably of stout material such as canvas, to give considerable rigidity to the float when the tubes are inflated, and provision is made for insertion and removal of the tubes from their respective compartments and for admitting and draining water into and from the compartments so that waterproofing material is unnecessary, thus giving the casing greater life without undue expense.

Various other objects, advantages and features of our invention will become apparent from the following detailed description.

Our invention resides in the float, surf-mattress, float casing, casing blank, constructions and features of the character hereinafter described and claimed.

For an illustration of some of the many forms our invention may take, reference is to be had to the accompanying drawings, in which:

Fig. 1 is a plan view showing a float as constructed in accordance with our invention;

Fig. 2 is an elevational view of the float shown in Fig. 1;

Fig. 3 is a transverse, vertical sectional view, partly in elevation, taken on the line 3—3 of Fig. 1 looking in the direction of the arrows;

Fig. 4 is a longitudinal, vertical sectional view, partly in elevation, taken on the line 4—4 of Fig. 1 looking in the direction of the arrows;

Fig. 5 is a fragmentary perspective view showing a feature of the invention;

Fig. 6 is a fragmentary, vertical sectional view, partly in elevation, showing another feature of the invention;

Fig. 7 is a plan view showing the blanks from which are formed the enclosing casing of our novel float;

Fig. 8 is a perspective view showing a modification of the invention;

Fig. 9 is a fragmentary perspective view showing another modification of the invention;

Figs. 10 through 16 inclusive represent a more simplified modification of our invention.

Fig. 10 is a perspective view showing this modification of the invention.

Fig. 11 is a fragmentary perspective view taken on the line 11—11 of Fig. 10 looking in the direction of the arrows.

Fig. 12 is a transverse vertical sectional view, partly in elevation and taken on the line 12—12 of Fig. 10 looking in the direction of the arrows.

Fig. 13 is a transverse vertical sectional view, partly in elevation, showing a modification of Fig. 12.

Fig. 14 is a plan view of the blank which forms the upper side of the casing for the float shown in Fig. 10.

Fig. 15 is a plan view showing the blank from which the lower side of the casing is formed.

Fig. 16 is a plan view showing in detail the manner in which the blanks are stitched together to show the feature shown in Fig. 11.

At seashore resorts, it is customary for many bathers to "ride" the surf or breakers and, to facilitate the enjoyment of this sport, surf boards and "mattresses" have been used to some extent. However, the use of such boards is objectionable in certain respects and the known mattresses have certain objections. Therefore we have devised a surf "float" of the character hereinafter described. While the preferred use of the invention is as stated above, it is to be understood that the invention is not to be thus restricted. Thus, the herein described float may be used for various other purposes such, for example, as a life preserver, as a "boat" for children, as a rest station in a pool, as an anchored buoy, etc.

Referring particularly to Figs. 1, 2, 3, 4, 7, 10, 11, 12 and 13, the novel float of our invention is shown as comprising an outer casing or envelope A formed preferably from suitable flexible material such, for example, as rubber or, as herein illustrated, from canvas or other fabric. Preferably, the casing A defines two compartments

separated by a transverse partition $\mathbb{I}$ formed in any suitable manner, for example, as hereinafter described.

In accordance with one method, the casing A 5 may be formed by suitably securing together two similarly shaped blanks a, a of the character shown in Fig. 7. As clearly appears, each of these blanks comprises generally circular, diaphragm-like end sections b, b merging into a central neck 10 section c along a common section line having a length somewhat less than the diameter of said end sections b, b .

In order to form the casing A, each of the blanks a, a is folded along the neck section line 15 c to obtain a configuration as indicated at d in Fig. 5. Thereupon, these folds are stitched or otherwise suitably secured together, the stitch lines in the assembled construction being indicated by the broken lines e , Figs. 3 and 5, and 20 said stitch lines terminating short of the ends of the folds, Fig. 3. In this manner, each blank a is formed with a folded section d which may be transversely disposed with respect to the blank plane. When said blanks are assembled in 25 30 symmetrical relation as described above, these two folds d are disposed in facing relation, Fig. 5, and each fold d has secured thereto, in suitable manner, the fabric strip $3a$ of a slide fastener 3. In lieu of a slide fastener, it will be understood 35 that any other suitable means may be provided for readily opening and closing this passage. Or, if desired, suitable means may be provided for permanently securing the aforesaid folds d together so as to form the desired trans- 40 verse wall $\mathbb{I}$.

After completion of the foregoing, the two blanks a, a are symmetrically disposed and the margins thereof are stitched or otherwise permanently secured together in suitable manner. All 45 of the circular margins of the blanks a, a are thus permanently secured together except in one area of the casing A where adjacent margins of the blanks a, a form a passage provided with means for readily opening or closing the same, this means being of any suitable character such, 50 for example, as a slide fastener 2. This marginal stitching extends closely adjacent the ends of the aforesaid stitch lines e and, therefore, the two blanks are maintained in the desired casing-forming configuration.

In accordance with our invention, each compartment of the casing A is adapted to receive a buoying means which may be of any suitable character. As herein illustrated, such buoying means is exemplified as a conventional inner tube 55 B of an automobile tire, each compartment of said casing A receiving a single tube B. In order to position the tubes B in their respective casing compartments, the slide fasteners 2 and 3 are operated to open the passage into the casing A and the passage through the partition $\mathbb{I}$. Then, a tube B is placed in that compartment of said casing A at the right, Fig. 1, and the slide fastener 3 is operated to close the partition passage. 60 Finally, a tube B is placed in that compartment of said casing A at the left, Fig. 1, and the slide fastener 2 is operated to close the passage into the casing.

In accordance with the invention, each end 65 section b of one of the blanks a is provided with a passage f sufficiently large for the passage therethrough of a human hand and a conduit 4 delivering air under pressure through a nozzle 5 adapted to be applied to the valve stem 6 of the tube B, the passages f , preferably, being cen-

trally located in the respective end sections b . In this manner, each tube B may be inflated to suitable extent after having been inserted in the casing A in non-inflated or partially inflated condition as described above.

Further in accordance with the invention, each end section b of both blanks a, a is provided with a series of small passages g arranged, preferably, in generally circular rows and utilizable as hereafter described. These passages g should be so 10 located that, when the tubes B are inflated, they are disposed closely adjacent the surfaces of the respective tubes B but are not sealed thereby, Fig. 4. Inasmuch as the partition $\mathbb{I}$ is stout enough to cause adjacent surfaces of the two 15 tubes B to conform to the sector line $\mathbb{I}$ and thus assume flattened portions as shown in Fig. 1, the adjacent passages g should take a corresponding configuration so as to avoid sealing thereof by the inflated tubes B. It will be understood 20 that the above described passages f and g should be suitably bound or have the respective grum- 25 mets or eyelets 7 associated therewith so as to avoid tearing of the casing material.

In view of the foregoing, it follows that the 30 above described compartments for the respective tubes B are provided, preferably, with a plurality of passages as described. In addition, it may be desirable to eliminate other casing material from one or both sides of said compartments in order 35 to save material, decrease weight, etc.

Although the hereinbefore described transverse partition $\mathbb{I}$ has been disclosed as formed in a particular manner, it shall be understood that the invention is not to be so limited. Thus, for example, said partition $\mathbb{I}$ may be of any suitable material utilizable or formed in any suitable manner for preventing undesirable displacement of the tubes B after they have been inflated. For example, the partition or barrier may be formed 40 by permanently stitching the two blanks together along their respective fold-lines CC as will hereinlater be described in more detail, and such modified partition or barrier need not be provided with an opening or passage through which a tube 45 is to be passed. Also the slide fastener opening 2 in the end of compartment A, Figs. 1 and 4, may be omitted. A construction of this type is simple, 50 cheaper to construct and less apt to get out of order. With a construction of this character and 55 as indicated in Figs. 8 and 10, it will be understood that each compartment of the float casing should be provided with a suitably located passage so that a tube B may be passed thereinto and withdrawn therefrom.

Referring particularly to Figs. 10, 11, 12, 14 and 15, the modified casing A mentioned above, in which the transverse partition $\mathbb{I}$ affords no access between the tube compartment, Figs. 11 and 12, will now be described in more detail.

The casing A defines two compartments separated by a transverse partition $\mathbb{I}$, and is formed by suitably securing together two similarly shaped blanks a, a of the character shown in Figs. 14 and 15. These blanks are substantially 65 of the same configuration as the blanks a, a shown in Fig. 7 except the substantially circular end sections b, b do not merge together but are separated by a narrow rectangular shaped neck section C, the necessity for which will now be 70 explained. Looking at Figs. 3 and 5 it will be seen that there is not sufficient material in the blanks of Fig. 7 to allow their respective folds d to be directly stitched to one another, had it been 75 so desired, but the fabric strip $3a$ of the slide-

fastener 3 was employed to span the gap between and fasten the respective folds together to form the desired transverse wall 1.

However, in the present modification, Fig. 11, it is desirous to eliminate the slide-fastener opening in the partition 1 and stitch the folds of the respective blanks directly together so as to form a permanently closed transverse partition between the two tube compartments of the casketment. Therefore, in lieu of the slide-fastener strip, it is necessary to provide additional material for more extensive folds. It is for this reason that the narrow strip of material C is left between the two end sections b, b when cutting the blanks of Figs. 14 and 15.

In order to form the casing partition 1, each of the blanks a, a is folded along their respective line c, c, Figs. 14, 15 and 16, which line runs through the middle of each central neck section C. The respective folds are then stitched securely along their respective stitch line e, e Fig. 16, these stitch lines in the assembled construction being indicated by the broken lines e, e, Figs. 11 and 12, said stitching being terminated short of the ends of the folds, Fig. 16. The blanks are then symmetrically superimposed one on the other so that their respective folds are disposed in facing relationship, Fig. 11, and slightly overlapping. The folds are then stitched to one another along a line adjacent to and parallel with their respective center line c, c.

Having thus formed the transverse partition wall between the two tube compartments, the corresponding circular end sections b of the respective blanks are secured together by stitching about their circumferential margins. This marginal stitching extends closely adjacent the end lines of the aforesaid stitch lines e, Fig. 11, maintaining the blanks in casing forming relation.

It is preferable to have all seam selvages disposed on the inner surface of the casing. This may be done by stitching the corresponding end sections together while they are reversed, and after each is stitched turning them right side out.

In accordance with the present modification a somewhat larger central opening f is provided in each compartment, Fig. 10, to allow not only for the inflation of the tubes therethrough, but also for the insertion and removal of the deflated tubes therefrom. The casing is also provided on both top and bottom with the heretofore described drainage passages framed with the eyelets 7.

From a consideration of Figs. 1, 4 and 11 it will be observed that the transverse partition 1 serves to prevent undesired shifting movement of the tubes within the casing. This partition 1 in conjunction with the interior casing surfaces adequately confines the inflated tubes in their respective desired positions. During the process of inflating, however, the tubes have a tendency to distort or over-ride one another due to unequal pressure being exerted in opposite directions against the partition. In order to overcome this tendency of the tubes to over-ride one another a modified manner of stitching the fold in each blank is shown in Fig. 13. By thus having the partition or fold-defining stitch lines converge towards one another, a rounded-out V or wedge-like surface is presented, which centers the tubes and guides them into their desired relationship while being inflated.

If desirable, the casing A may have a plurality of fabric loops 8 suitably attached thereto and, further, if desired, each side of said casing A may have the ends of a rope 9, or equivalent, attached

thereto in suitable manner, as by the tabs 10, Fig. 2. These loops 8 or ropes 9 may be grasped by hand when the float is to be transported from place to place. It shall be understood, however, that the invention is not to be limited to the utilization of the loops 8 and ropes 9.

In view of the foregoing description, it will be understood that the float, when disassembled, may readily be transported with the tubes B non-inflated and with the casing A in roll or package 10 formation. Little space is required under these circumstances. When the float is to be used, the tubes B are inserted as described. Thereafter the tubes B are inflated by air under pressure as obtained from a suitable source.

Assuming that the size of the casing A is properly proportioned to the diameter of the tubes B, the float, when thus assembled, appears substantially as shown on the drawings. That is, said tubes B maintain the casing A under tension with slight, if any, free space therein except that encompassed by the tubes B.

Inasmuch as the surfaces of the casing A spanning the tubes B are thus maintained under tension and the connecting sector 1 of the two compartments is of sufficient width, it follows that the upper casing surface of the float, when in the water, is maintained plane and taut and advantageously serves as a quite rigid support for the bather recumbent thereon without objectionable sag of the upper casing surface.

The float, when assembled in operative condition as described above, weighs but a few pounds and may readily be carried from place to place or into the surf. When used for surf-riding purposes, it may easily be mounted by the bather and, while passing through the surf, the resiliency afforded by the tubes B is a factor rendering injury to another bather unlikely in the event of a collision.

After the ride through the surf has been completed, the bather may readily elevate the float whereupon such water as remains trapped therein will escape from the interior thereof by way of the passages f and g. As stated, substantially the only free space within the float is that encompassed by the tubes B and, therefore, the provision of the aforesaid passages renders it possible to easily drain the float in a substantially complete manner in but a few moments. When thus drained, the weight of the wet float is only slightly greater than when dry.

The invention, as hereinbefore specifically described, relates to the provision of a float comprising a single pair of tubes B. It shall be understood, however, that the invention is not to be thus limited. Thus, for example, from a broad aspect, the float of our invention may be formed by using a single tube B, either of the endless or non-endless type, and an associated casing A 60 having a configuration corresponding therewith.

Further, the float of our invention may comprise more than a single pair of the tubes B. Thus, as illustrated in Fig. 8, there may be provided a modified casing A 1 which, by the provision of two transverse partitions 1, forms three compartments each of which is adapted to receive a tube.

It will be understood that the casing or envelope of our novel float may be constructed otherwise than as hereinbefore described. Thus, as indicated in Fig. 9, the casing may advantageously be formed, if desired, from upper and lower blanks or sheets h, h, these being secured together by a transverse peripheral casing section i, all of

these casing sections being stitched or otherwise secured together in any suitable manner.

Under some circumstances, the hereinbefore described casings may be formed from suitable waterproof material such as rubber, treated canvas, etc. With such a construction, the above described passages *f* and *g* and the openings *T*, are omitted and the valve stems of the tubes *B* extend through suitable water-tight connections 10 terminating exteriorly of the casing.

With either a waterproof or non-waterproof float casing, it may be desirable to pack suitable buoyant material, such as balsa wood, cork or the like in the space encompassed by the tubes *B*.

15 Further, under some circumstances, it may be desirable to support each tube *B* by a suitable interior rim which is adapted to be detachably associated therewith in suitable manner.

20 While the invention has been described with respect to certain particular preferred examples which give satisfactory results, it will be understood by those skilled in the art after understanding the invention, that various changes and modifications may be made without departing 25 from the spirit and scope of the invention and it is intended therefore in the appended claims to cover all such changes and modifications.

25 This is a continuation of our application for Letters Patent Serial Number 220,456, filed July 30 21, 1938.

What is claimed as new and desired to be secured by Letters Patent is:

30 1. A float comprising a casing arranged to define a plurality of chambers, and endless expandable tubes positioned in the respective chambers, said casing comprising upper and lower sections spanning the space across said tubes, said tubes, when inflated, maintaining said upper and lower casing sections substantially taut and spaced a substantial distance apart so as to define 35 a plurality of chambers bounded in part by said tubes, said chambers having passages admitting a quantity of water, during use of the float, and for draining the water from said chambers when the float is elevated from the water.

40 45 2. A float comprising a casing arranged to define a plurality of chambers, and endless expandable tubes positioned in the respective chambers, said casing comprising upper and lower sections spanning the space across said tubes, said tubes, when inflated, maintaining said upper and lower casing sections substantially taut and spaced a substantial distance apart so as to define 50 a plurality of chambers bounded in part by said tubes, said chambers having passages admitting a quantity of water, during use of the float, and for draining the water from said chambers when the float is elevated from the water, said tubes, when inflated, imparting buoyancy to the float, 55 said casing being constructed and arranged to prevent undesired shifting movement of said tubes.

60 65 3. A float comprising a casing arranged to define a plurality of chambers, and endless expandable tubes positioned in the respective chambers, said casing comprising upper and lower sections spanning the space across said tubes, said tubes, when inflated, maintaining said upper and lower casing sections substantially taut and 70 spaced a substantial distance apart so as to define a plurality of chambers bounded in part by said tubes, said chambers having passages admitting a quantity of water, during use of the float, and for draining the water from said chambers when the 75 float is elevated from the water, and a transverse

partition barrier means between said chambers for preventing undesired shifting movement of said tubes.

4. A float comprising a casing arranged to define a plurality of chambers, and endless expandable tubes positioned in the respective chambers, said casing comprising upper and lower sections, spanning the space across said tubes, said tubes, when inflated, maintaining said upper and lower casing sections substantially taut and 10 spaced a substantial distance apart so as to define a plurality of chambers bounded in part by said tubes, and transverse partition barrier means between said chambers for preventing undesired shifting movement of said tubes. 15

5. A float comprising a casing having a passage giving access to the interior thereof, means for readily opening or closing said passage, a transverse partition dividing said casing into separate annular tube enveloping chambers and having a 20 passage therethrough, means for readily opening or closing said second named passage, an endless expandable tube adapted to be positioned in one of said chambers after both of said passages have been opened, and an endless expandable tube 25 adapted to be positioned in another of said chambers after said second named passage has been closed, said casing comprising upper and lower sections spanning the space across said tubes, said tubes, when inflated, maintaining said 30 upper and lower casing sections substantially taut and spaced a substantial distance apart so as to define a plurality of chambers bounded in part by said tubes, said tubes, when inflated, imparting buoyancy to the float. 35

6. A float comprising a casing having a passage giving access to the interior thereof, means for readily opening or closing said passage, a transverse partition dividing said casing into separate annular tube enveloping chambers and having a 40 passage therethrough, means for readily opening or closing said second named passage, an endless expandable tube adapted to be positioned in one of said chambers after both of said passages have been opened, and an endless expandable tube 45 adapted to be positioned in another of said chambers after said second named passage has been closed, said casing comprising upper and lower sections spanning the space across said tubes, said tubes, when inflated, maintaining said 50 upper and lower casing sections substantially taut and spaced a substantial distance apart so as to define a plurality of chambers bounded in part by said tubes, said chambers having passages admitting a quantity of water, during use of the float, 55 and for draining the water from said chambers when the float is elevated from the water.

7. A float comprising a casing having a passage giving access to the interior thereof, means for readily opening or closing said passage, a transverse partition dividing said casing into separate chambers and having a passage therethrough, means for readily opening or closing said second named passage, the opposite ends of said casing being of generally circular configuration, and said 60 partition being transversely arranged with respect to the longitudinal casing axis, an endless expandable tube adapted to be positioned in one of said chambers after both of said passages have been opened, and an endless expandable tube 65 adapted to be positioned in another of said chambers after said second named passage has been closed, said tubes, when inflated, imparting buoyancy to the float. 70

8. A float comprising a casing having a pas- 75

5 sage giving access to the interior thereof, means for readily opening or closing said passage, a transverse partition dividing said casing into separate chambers and having a passage there-through, means for readily opening or closing said second named passage, the opposite ends of said casing being of generally circular configuration, and said partition being transversely arranged with respect to the longitudinal casing 10 axis, an endless expandible tube adapted to be positioned in one of said chambers after both of said passages have been opened, and an endless expandible tube adapted to be positioned in another of said chambers after said second 15 named passage has been closed, said chambers having passages admitting a quantity of water, during use of the float, and draining the water from said chambers when the float is elevated.

9. A casing for a float of the character de- 20 scribed, said casing being formed from a pair of blanks secured in casing-forming relation at their edges and each end of said casing being of generally circular configuration, a transverse partition dividing said casing into separate 25 chambers, said chambers each having a passage giving access to the interior thereof for the insertion of an annular shaped inflatable tube, said casing comprising upper and lower sections spanning the space across said tubes, said tubes, 30 when inflated, maintaining said upper and lower casing sections substantially taut and spaced a substantial distance apart so as to define a plurality of chambers bounded in part by said tubes.

10. In a float of the character described, a 35 flexible casing and two annular tubes adapted to be enclosed therein, said tubes, when inflated, lying in the same plane and each being substantially tangent to the other; said casing comprising upper and lower casing sections spanning the space across said inflated tubes and 40 said upper and lower sections being held taut and substantially parallel to each other by said tubes, a plurality of passages through at least one of said casing sections for admitting water to the interior of the casing as ballast for the 45 float when in use, said passages being located adjacent the circumferences of at least one of said sections and near the tubes to allow for complete drainage when the float is raised.

11. A float comprising a casing formed from 50 flexible material, and two annular shaped buoying means enclosed within said casing; said buoying means both being positioned in a common plane and each substantially tangent to

the other, means formed in said casing for inserting or removing said buoying means.

12. A casing of flexible material for a float of the character described, said casing comprising a pair of blanks, each blank having substantially the configuration of a figure 8 with a short central neck section disposed between two generally circular sections, each blank secured together around its edges in casing-forming relation, the respective neck portions being joined 10 together to form a transverse partition dividing said casing into separate chambers, each adapted to enclose an annular inflatable tube.

13. A casing of flexible material for a float of the character described, said casing comprising a pair of blanks, each blank having substantially the configuration of a figure 8 with a short central neck section disposed between two generally circular sections, each blank secured together around its edges in casing-forming relation, the respective neck portions being joined 15 together to form a transverse partition dividing said casing into separate chambers, each adapted to enclose an annular inflatable tube, a plurality of annular series of drainage elements in 20 said casing for draining water from said chambers, and means opening into each chamber through which a tube may be inserted and inflated.

14. A casing for a float of the character de- 30 scribed, said casing comprising a pair of blanks, each blank secured to the other in casing-forming relationship at its edges, each of said blanks being of generally circular configuration and having a central neck portion disposed there- 35 between, said respective neck portions being joined together to form a partition dividing said casing into separate chambers, each of said chambers adapted to enclose an annular inflatable tube.

15. A float casing of flexible material adapted to separably enclose therein two substantially annular expandible tubes, said casing comprising a pair of blanks, each secured to the other in casing-forming relationship at its edges, a trans- 45 verse partition dividing said casing into two separate substantially circular tube-enclosing chambers, a plurality of annular series of drainage elements in said blanks for draining water from 50 said chambers, and means opening into each chamber through which the respective tubes may be inserted and inflated.
